UNITED STATES PATENT OFFICE.

HORMISDAS E. BRUNELLE, OF ST. PAUL, MINNESOTA.

WORKMAN'S SCAFFOLD

1,110,881.

Specification of Letters Patent. Patented Sept. 15, 1914.

Application filed May 31, 1913. Serial No. 770,844.

To all whom it may concern:

Be it known that I, HORMISDAS E. BRUNELLE, a citizen of the United States, residing at St. Paul, in the county of Ramsey and 5 State of Minnesota, have invented certain new and useful Improvements in Workmen's Scaffolds, of which the following is a specification.

My invention relates to improvements in 10 workmen's scaffolds designed particularly for exterior support upon window sills, its object being to provide a construction which will be easy of adjustment to different thicknesses and constructions of walls and window sills, and which will be particularly 15 strong and rigid when supported in position for use.

To this end the invention consists in the 20 features of construction, combination, and arrangement of parts hereinafter described and claimed.

In the accompanying drawings forming 25 part of this specification, Figure 1 shows a perspective view of my improved scaffold arranged in connection with a window sill, showing the window sill and wall in section; and Fig. 2 is a side view of the scaffold in folded position.

Referring to the drawings, A represents a 30 window sill, and B the face of the outside wall. C represents the face of the inside wall. The supporting frame D of the platform E is formed with downwardly extending feet 2 to rest upon the outer ledge. Having pivotal connection 3 with the outer end 35 of the platform framework are downwardly extending arms 4, the lower ends of said arms being connected by toggle links 5 and 6 with the brackets 7 slideable in slots 8 in the sides of the platform frame. The arms 4 and toggle links 5 and 6 with brackets 7 are 40 duplicated on opposite sides of the scaffold, and preferably connected as by a cross bar 9. Projecting upwardly and toward the platform E from the inwardly projecting sides 45 of the platform framework 2 are the arms 10. A cross bar 11 connects the arms 10 and supports the frame 12, the cross bar 11 constituting a hinge connection between the 50 frame 12 and platform. The frame 12 includes a central bar 13 forming a support for a slideable bracket 14 through which is screw threaded a bolt 15.

In use, the platform will be positioned 55 upon the window sill, as shown in Fig. 1

of the drawings, with the lower ends of the toggle links 5 bearing against the outer wall of the building and the bolt 15 screwed into contact with the inner wall of the building below the window sill. In positioning the scaffold upon the window sill the bracket 14 will, of course, be set at the proper position upon the bar 13 to adjust the scaffold to the particular construction of wall and sill. The screwing inward of the bolt 15 to tighten 60 the same against the adjacent wall, will pull the lower ends of the braced toggle arms 5 tightly against the outer wall to hold the platform in position. The slideable brackets 7, having pivotal connection with the 65 arms 4 and links 5 and 6, will assist in collapsing the scaffold, as shown in Fig. 2.

In those scaffolds of the prior art which are known to me, the outer bearing of the supporting structure against the wall is 70 accomplished by the ends of the diagonal brace rods, corresponding to applicant's element 4, coming in contact with the outer face of the wall. It will be noted that in the present structure the free end of the 75 toggle lever 5 is provided with an enlargement below the pivoted connection thereof with the brace arm 4 which bears against the outer face of the wall, while the upper end of the toggle lever 6 is connected to the 80 carriage or bracket 7. An additional function of the brackets 7, then, is to permit such necessary play of the upper end of the toggle, when the latter is extended, as is necessary to properly position the supporting 85 structure in its unfolded condition and to permit the lower ends of the levers 5 to secure a proper footing against the outer face 90 of the wall regardless of any irregularities or obstructions that may exist thereon. 95

As will be evident I secure a construction which is easily adapted to different types of sill and thicknesses of wall and in addition one that is particularly strong and rigid when supported for use, as shown in Fig. 100 1, and collapsible into a compact condition, as shown in Fig. 2.

I claim as my invention:

1. A window scaffold comprising in combination, a platform, a frame supporting said platform, an adjustable means carried by said frame in position to be set in contact with the inner face of a wall, an extensible means carried by said frame for bracing the latter against the outer face of the wall, said 105 110

extensible means consisting of rearwardly extending braces pivoted to said frame, toggle connections between the free ends of said braces and said frame, longitudinally slideable brackets carrying the frame-ends of said toggle connections and bearing-feet formed on the lower ends of said toggle connections for contact with the face of the wall.

- 10 2. A window scaffold comprising in combination, a platform, a frame supporting said platform, an adjustable means carried by said frame in position to be set in contact with the inner face of a wall, an extensible means carried by said frame for bracing the latter against the outer face of the wall, said extensible means consisting of foldable toggles having a sliding connection with said frame, bearing feet on the lower ends of said toggles for contact with a wall-face, and braces extending from the lower ends of said toggles to the outer ends of said frame.

- 15 3. A window scaffold comprising in com-

bination, a platform, a frame supporting said platform, an adjustable means carried by said frame in position to be set in contact with the inner face of a wall, an extensible means carried by said frame for bracing the latter against the outer face of the wall, said extensible means consisting of braces pivoted to the outer end of said frame, and extending to points adjacent the outer wall face, toggle levers having their lower ends connected to the free ends of said braces, bearing feet on said toggle levers for contact with the wall face, and brackets carried by the upper ends of said toggle levers, and having longitudinally slideable connections with said frame.

In testimony whereof I affix my signature 40
in presence of two witnesses.

HORMISDAS E. BRUNELLE.
